UNITED STATES PATENT OFFICE.

CLAUDIUS DORNIER, OF FRIEDRICHSHAFEN-ON-THE-BODENSEE, GERMANY, ASSIGNOR TO DORNIER-METALLBAUTEN G. M. B. H., OF FRIEDRICHSHAFEN-ON-THE-BODENSEE, GERMANY.

TRUSS HAVING A PLURALITY OF STRUTS FOR THE WINGS OF AEROPLANES.

Application filed May 12, 1927, Serial No. 190,879, and in Germany June 14, 1926.

This invention relates to an aeroplane wing having a plurality of struts and to its connection with the body. The supporting plane comprises a relatively thick central beam and 5 two thinner front and rear beams. The central beam serves as a main girder and in normal flying has to bear about half the total load. The other two beams can therefore be placed a considerable distance forward or 10 rearward, because the web depth then still available in the wing cross section is still sufficient to stand high stresses. By this enlargement and subdivision of the distance between beams a construction is practicable 15 with lighter wing ribs than would be necessary in the arrangements with only two beams. In addition, this arrangement of three beams presents the possibility of effecting the connection of the main beam in the 20 centre with the body exclusively by means of tensile members, while the compression and tension resisting connections of the two other beams connecting the wings with the body are thereby relieved to a substantial extent. Owing 25 to the greater distance of the outer beams from the centre of the wing, moreover, by the alteration in the torque of the air forces during variations in angular position, only relatively small forces act upon the outer 30 beams and their connection with the body, owing to the increase in the length of the lever arms.

A further advantage of the invention is obtained if the lateral supporting struts between the wing and the body are not attached 35 to the wing at the same distance from the central plane of the flying machine. The forces reaching the beams are then diminished owing to the fact that the smaller lever arm brings 40 about a relieving of the adjacent beams through the medium of the wing ribs.

The essential features of the invention are illustrated in various constructional examples in the accompanying drawings, wherein

Figure 1 shows in section a wing *a* with 45 three beams. The central beam *b* is connected by a cable *c* with the body, which in this figure has been omitted as unnecessary. The front and rear beams *d* and *e* are supported from the body by struts *f*.

In Figure 2 the wing *a* is again secured to the body *g* by struts or cables *f* and *c*. The lateral supporting struts *f'* and *c'*, which are preferably likewise attached to the beams, 50 here lie in one plane.

In the case of the construction according to Figure 3 the struts *f'* and *c'* do not coincide in front elevation, but their points of attachment to the wing do not lie at equal distances from the central plane.

What I claim is:—

1. A supporting wing for aeroplanes comprising a main cross beam and two auxiliary cross beams, a tension member capable of resisting tensile forces only connected to the 65 main cross beam and struts capable of acting both as pressure and tension members connected to the auxiliary cross beams, as set forth.

2. A supporting wing for aeroplanes as set 70 forth in claim 1 and having in addition lateral struts capable of acting both as pressure and tension members connected to the main and auxiliary cross beams at points which are not at equal distances from the central plane 75 of the wing, as set forth.

In testimony whereof I have signed my name to this specification.

CLAUDIUS DORNIER.
